CLAIM

The ornamental design for a wine cabinet, as shown and described.

DESCRIPTION

FIG. 1 is a perspective view of a wine cabinet, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof; and,

FIG. 9 is a partially enlarged view of the area labeled 9 in FIG. 1, showing design of a door of the wine cabinet.

The evenly broken lines shown in the figures depict unclaimed portions of the wine cabinet; the dash-dot type broken line discloses the unclaimed boundary of the isolated view only; the broken lines form no part of the claimed design.
